US0D1020958S

(12) **United States Design Patent** (10) Patent No.: **US D1,020,958 S**
(45) Date of Patent: ** Apr. 2, 2024

(54) **FLOTATION APPARATUS FOR SWIMMING**

(71) Applicant: **Hubei Anbeier Intelligent Technology Co., Ltd.**, Huanggang (CN)

(72) Inventors: **Wu He**, Zhongshan (CN); **Xi He**, Zhongshan (CN); **Hui Dong**, Zhongshan (CN)

(73) Assignee: **Hubei Anbeier Intelligent Technology Co., Ltd.**, Huanggang (CN)

(**) Term: **15 Years**

(21) Appl. No.: **29/903,597**

(22) Filed: **Sep. 26, 2023**

(30) **Foreign Application Priority Data**

May 10, 2023 (CN) 202330271981.3

(51) **LOC (14) Cl.** **21-03**

(52) **U.S. Cl.**

USPC **D21/803**

(58) **Field of Classification Search**

USPC D21/803, 804, 808, 835; 441/40, 126, 441/129, 130, 132; 114/345

CPC B63B 34/52; B63B 34/50; A47C 15/006; A63H 23/10

(57) **CLAIM**

The ornamental design for a flotation apparatus for swimming, as shown and described.

DESCRIPTION

FIG. 1 is a front perspective view of a flotation apparatus for swimming, showing our new design;

FIG. 2 is a rear view thereof;

FIG. 3 is a left side view thereof;

FIG. 4 is a front view thereof;

FIG. 5 is a right side view thereof;

FIG. 6 is a top view thereof; and,

FIG. 7 is a bottom view thereof.
